UNITED STATES PATENT OFFICE.

RANDALL McFARLAN, OF CINCINNATI, OHIO.

NONRETURN VALVE

Application filed January 3, 1921. Serial No. 434,494.

To all whom it may concern:

Be it known that I, RANDALL McFARLAN, a citizen of the United States of America, and resident of Cincinnati, in the county of 5 Hamilton and State of Ohio, have invented a new and useful Improvement in a Non-return Valve, of which the following is a specification.

This invention relates to the class of
10 valves which are interposed between each
boiler of a series of boilers and the main
steam line, and which are provided with
two seats, against one of which the valve is
seated in case there is no pressure in the
15 boiler, and against the other of which the
valve is seated in case of any break in the
main steam line.

In valves of this class heretofore in use, there has been a tendency for the valve to chatter, particularly when the main steam line supplies a reciprocating engine. In such instances the non-return valve does not become thoroughly raised from its seat and therefore upon each closing off of the steam the valve returns to its seat, to be raised again when the flow of steam takes place.

The object of the present invention is to provide a means for insuring a full rising of the non-return valve from its seat and to maintain it in that position whilst there is pressure in its boiler, or until it is carried to the opposite seat by a break in the main steam line.

Another object is to provide a simple and
35 efficient device of the type referred to.

These and other objects are attained by the means described herein and disclosed in the accompanying drawing in which:—

Fig. 1 is a plan view of a valve, embodying my invention parts being broken away.

Fig. 2 is an enlarged section view on line 2-2 of Fig. 1.

Fig. 3 is a sectional view on line 3—3
of Fig. 4.
45 Fig. 4 is a sectional view on line 4—4
of Fig. 3.

Fig. 5 is a sectional view on line 5-5 of Fig. 3.

50 My invention comprises a housing A with-
in which is mounted a valve B adapted
to control the flow of a fluid, such as steam,
from the boiler C and a valve governor D
or a steam locking cylinder.

55 The housing A is adapted to be mounted upon the boiler C so that the chambers therein will communicate with the interior

of the boiler C. The housing A is preferably made of a head section a and a body section a' , adapted to be mounted upon one another by any suitable means such as bolts a^2 . A secondary valve seat a^3 is mounted intermediate the chamber a^4 formed within the head of the housing and the secondary chamber a^5 formed within the body of the housing. A primary valve seat a^6 is mounted within the body a' of the housing, intermediate the primary chamber a^7 formed therein and the secondary chamber a^5 . A reciprocating stem a^9 is mounted upon the housing and extends therewith. The outer end of the stem a^9 is threaded and engages a threaded bearing a^{12} mounted upon the housing A. A handle a^{11} is mounted upon the exterior end of the stem a^9 whereby the stem a^9 may be rotated and thereby be reciprocated longitudinally in and out of the housing A so as to seat the valve B upon the primary valve seat a^6 .

The compound valve disk B is reciprocally mounted within the secondary chamber a^5 of the housing by means of the primary valve stem b extending from one side of the valve B. The primary valve stem is reciprocally mounted upon a spider a^8 extending from the valve seat a^6 . The secondary valve stem b' extends from the opposite side of the valve B and extends thru the secondary valve seat a^3 and into the chamber a^4 within the head of the housing. The secondary valve stem b' has a central bore b^2 into which extends the inner end of the reciprocating stem a^9 . The secondary valve stem is adapted to reciprocate longitudinally upon the stem a^9 . The compound valve disk B has formed on one of its sides a primary valve b^3 adapted to engage the primary valve seat a^6 , and upon its opposite side a secondary valve b^4 adapted to engage the secondary valve seat a^3 . Mounted upon the secondary valve stem b' is a collar b^5 having the pins b^6 extending therefrom upon which are mounted the roller bearings b^7 .

The valve B is controlled by the valve governor D. This governor mechanism comprises a plunger casing d mounted upon housing A and having within it a plunger chamber d' communicating with the primary chamber a⁷ by means of a duct d². Contained within the chamber d' is a plunger d³, one end of which extends from the casing d and has mounted upon it a roller d⁴. A

revoluble shaft d^5 is mounted upon the housing A and extends thru the head thereof. Upon the outer end of the revoluble shaft d^5 is mounted a cam d^6 in alignment with the roller d^4 on the plunger d^3 . The cam has two lobes d^{14} and d^{15} between which is formed a detent d^{16} . The shaft d^5 is secured against lateral displacement by forming a shoulder d^7 thereon engaging the bearing b^8 mounted upon the housing A. Suitable packing d^9 is mounted about the shaft d^5 by means of a gland d^{10} . Mounted upon the shaft d^5 interiorly of the chamber a^4 is an arm d^{11} having a yoke d^{12} formed thereon, the fingers d^{13} thereof engaging the roller bearing b^7 mounted upon the secondary stem b' . Rotation of the plunger is avoided by any suitable means such as the longitudinal slot d^{17} in casing d and the pin d^{18} mounted on the plunger and extending into slot d^{17} . A shoulder d^{19} is formed upon the inner wall of the plunger casing d so as to project into the plunger chamber d' . The plunger d^3 has a shoulder d^{20} intermediate its length adapted to engage the shoulder d^{19} formed on the casing d , thereby limiting the movement of the plunger, and the contact of the said two shoulders providing a steam proof connection augmenting the packing rings d^{21} mounted upon the plunger. The shoulders prevent the pressure of the steam within the plunger chamber from moving the plunger toward and upon the shaft d^5 so as to cause damage to any of the parts that might be injured by an uncontrolled movement of the plunger.

The operation of my device is as follows:

We will assume that the steam is being generated within the boiler C. In this position, assuming that the valve B had been moved upon the primary valve seat a^6 by means of the stem a^9 , by gravity, or by the pressure of the steam in the main steam line and that the stem a^9 has then been moved to a position as shown in Fig. 1, the plunger will be retained upon the base of chamber d' by the lobe d^{14} engaging the roller d^4 , or by gravity. The steam generated within the boiler C will enter the chamber d' thru the duct d^2 . When the pressure of the steam within the boiler equals that of the steam within the main steam line, the pressure of the steam within the boiler will push the plunger d^3 toward the revoluble shaft d^5 , and the movement of the valve B will be occasioned by the rotation of the shaft d^5 ; the roller d^4 on the plunger moving over the face of the lobe d^{14} , on the cam d^6 . These movements are all relative and simultaneous and will continue until the roller d^4 registers with the detent d^{16} , which registration will retain the valve B in a position intermediate with the primary and secondary valve seats. Slight fluctuations of the relative pressures with-

in the boiler and the main steam line will be insufficient to move the roller from the detent, wherefore the rattling and chattering referred to before is eliminated. Should a break occur in the main steam line, the steam within the boiler will cause the secondary valve upon B to engage its seat a^5 , thereby shutting off communication of the boiler C and the main steam line. This movement of the valve B causes the shaft d^5 to rotate and the roller leaves the detent and moves over the lobe d^{15} on the cam d^6 and the plunger d^3 is moved downward in the chamber d' . When the pressures have been substantially equalized, the pressure of the steam upon the plunger d^3 causes the plunger d^3 to again assume the position shown in Fig. 2 and thereby checks the valve B as it moves toward the seat a^6 and prevents chattering of the valve B. Slight fluctuations of steam pressures tending to move the valve between the two valve seats a^5 and a^6 , resulting from the use of boilers with reciprocating engines and the like will not affect the valve B to such an extent as to reciprocate the valve between its seats and thereby the chattering and the wear resulting therefrom is eliminated.

What I claim is:

1. The combination of a housing enclosing oppositely-facing valve-seats, a double-faced valve adapted to reciprocate between said seats, a valve-stem adapted to forcibly seat the valve against one of said seats, a valve-controlling device embodying a cylinder in communication with the supply-side of the housing, a piston working in said cylinder having a rod extending out through the cylinder, and means co-acting with said rod to positively actuate said valve.

105

2. In a non-return valve mechanism, a housing, two oppositely-facing valve seats enclosed therein, a double-faced valve working between said seats, a manually operable valve stem for seating the valve against the valve seat adjacent a supply source and adapted to be adjusted to permit the valve to seat itself against the other seat, and means for holding the valve intermediate the seats while fluid is passing through the housing from the supply-source, said means embodying a rock-shaft extending into the housing and connected to the valve in such manner as to reciprocate the valve relatively as the rock-shaft is actuated and fluid-actuated means operative upon the outer end of the rock-shaft and having constant connection with the supply-source of fluid.

115

3. In a non-return valve the combination of a housing, comprising a head and a body, a chamber within the head adapted to communicate with a main line, a primary and a secondary chamber within the body, the primary chamber being adapted to communicate with a boiler, a primary valve seat in

125

130

- termediate the primary and secondary chamber, a valve seat intermediate the chamber in the head and the secondary chamber, a valve within the secondary chamber adapted to engage the valve seats, a valve stem, a revolute shaft extending into the housing, and an arm mounted on the shaft and pivotally engaging the valve stem, a plunger casing, a plunger chamber within the casing communicating with the primary chamber, and a plunger within the plunger chamber and adapted to control the movement of the revolute shaft. 5
4. In a non-return valve the combination of a housing, comprising a head and body, a chamber within the head adapted to communicate with a main line, a primary and a secondary chamber within the body, the primary chamber being adapted to communicate with a boiler, a primary valve seat intermediate the primary and secondary chambers, a valve seat intermediate the chamber in the head and the secondary chamber, a valve within the secondary chamber adapted to engage the valve seats, a valve stem, a revolute shaft extending into the housing, an arm mounted on the shaft and pivotally engaging the valve stem, a plunger casing, a plunger chamber within the casing communicating with the primary chamber, a plunger in the plunger chamber adapted to engage a lobe when one of the valves is closed and to engage in the detent when the valves are open. 10
5. In a non-return valve the combination of a housing, comprising a head and a body, a chamber within the head adapted to communicate with a main line, a primary and a secondary chamber within the body, the primary chamber being adapted to communicate with a boiler, a primary valve seat intermediate the primary and secondary chamber, a valve seat intermediate the chamber in the head and the secondary chamber, a valve within the secondary chamber adapted to engage the valve seats, a valve stem, a collar mounted on the stem, pins mounted on the collar, a revolute shaft extending into the housing, an arm on the revolute shaft, a yoke on the arm, fingers on the yoke engaging the pins, a cam on the shaft, a plunger casing, a plunger chamber within the casing communicating with the primary chamber, and a plunger in the plunger chamber and engaging the cam. 15
6. In a non-return valve the combination of a housing, comprising a head and a body, a chamber within the head adapted to communicate with a main line, a primary and a secondary chamber within the body, the primary chamber being adapted to communicate with a boiler, a primary valve seat intermediate the primary and secondary chambers, a valve seat intermediate the chamber in the head and the secondary chamber, a valve within the secondary chamber adapted to engage the valve seats, a valve stem, a revolute shaft extending into the housing, an arm mounted on the shaft and pivotally engaging the valve stem, a cam mounted on the shaft, lobes on the cam and a detent formed between the lobes, a plunger casing, a plunger chamber within the casing communicating with the primary chamber, a plunger in the plunger chamber adapted to engage a lobe when one of the valves is closed and to engage in the detent when the valves are open. 20
7. In a non-return valve mechanism, a housing enclosing two oppositely-facing valve-seats, a double-faced valve working between said seats, a manually-operable valve-stem for seating the valve against the valve-seat adjacent the supply-source and adapted to be adjusted to permit the valve to seat itself against the other seat, and fluid-actuated means for holding the valve intermediate the seats while the fluid is passing through the housing from the supply-source, said means embodying a piston under constant pressure from the supply-source, a rock-shaft extending into the housing and having positive connection with the valve, and means co-acting between said piston and said rock-shaft for constantly tending to hold the valve in a position intermediate said valve-seats. 25

In testimony whereof, I have hereunto subscribed my name this 22nd day of December, 1920.

RANDALL McFARLAN.
